RAILWAY-TRAFFIC-GOVERNING APPARATUS.

Application filed April 25, 1922. Serial No. 556,506.

Our invention relates to railway traffic governing apparatus, and has for an object the provision of means for controlling traffic governing devices, such as railway signals, 5 from a distant point such as a despatcher's office. Another object of our invention is the provision of means for enabling a train despatcher or other official to be informed when a signal at a distant point changes 10 from one indication to another, thereby enabling him to locate a train.

We will describe one form of apparatus embodying our invention and will then point out the novel features thereof in claims. 15 In the accompanying drawings, Figs. 1^a and 1^b are diagrammatic views which, when placed end to end in the order named, illustrate one form of controlling and indicating apparatus embodying our invention, and which views will hereinafter be referred to collectively as Fig. 1. Fig. 2 is a view showing in side elevation one form of device which may be attached to the semaphore signals shown in Fig. 1 for transmitting an impulse combination and for governing one or more circuits. Fig. 3 is a top plan view of the device shown in Fig. 2. Fig. 4 is a perspective view of the code wheel forming part of the device shown in 20 Figs. 2 and 3. Fig. 5 is a sectional view on the line V of Fig. 3 looking in the direction indicated by the arrow. Fig. 6 is a view similar to Fig. 5 but showing a modified arrangement of gearing for causing repeated 25 operations of the code wheel instead of a single operation. Fig. 7 is a plan view showing one form of thermal circuit controller which may be used in connection with the apparatus shown in Fig. 1. Fig. 8 is a 30 side elevation of the controller shown in Fig. 7, and Fig. 9 is a sectional view on the line IX-IX of Fig. 8 looking in the direction indicated by the arrow.

Similar reference characters refer to similar parts in each of the several views.

Referring first to Fig. 1, the reference characters 22 and 22^a designate the track rails of a railway along which traffic normally moves in the direction indicated by the arrows. Traffic moving in such direction is governed by a series of signals S^a, S^b and S^c, which are located at suitable intervals and are controlled in the usual and well known manner by means of track circuits,

These track circuits are provided as usual by dividing the track rails by insulated joints 23 into a series of electrically isolated sections V-W, W-X, X-Y, etc., and the track circuit for each section comprises the track rails of the section, a source of current b, which as here shown is a battery, and a track relay designated by the reference character T with a suitable exponent. The controlling circuits for the signals will be explained hereinafter in discussing the operation of the system as a whole, it being sufficient to point out at the present time that each signal is controlled automatically by the track relays in such manner that the signal indicates "Stop" when the corresponding track section is occupied, "Caution" when the corresponding section is unoccupied and the section next in advance is occupied, and "Proceed" when the corresponding section and the section next in advance are both unoccupied.

In accordance with our invention these signals are controlled in part from a central location Z, which is usually the office of a train despatcher or other proper official. This control is affected by selectors associated with each signal, together with means in the despatcher's office for transmitting impulse combinations to which such selectors are responsive. These selectors may be Gill 80 selectors, Model E3, which selectors are well known commercial devices. In addition to this, the despatcher's office is provided with 85 selectors, and the signals are provided with apparatus for transmitting impulse combinations to the last-mentioned selectors, thereby giving the despatcher information 90 concerning the condition or operation of the signals.

In order to illustrate the operation of the apparatus, we will assume that the despatcher desires to be informed as to the indication given by signal S^c for the purpose of locating a train in the section governed by this signal and for which reason he also desires to determine when this signal moves to the stop position. To do this he operates code key A in the despatcher's office Z, thereby causing operation of a telegraph relay 24 through a circuit which includes a battery 25 and the contact 26 of the key A. The operation of relay 24 causes the transmission of an impulse combination from

the despatcher's office to the selectors at each of the signals S^A , S^B and S^C . The circuit over which these impulses are transmitted to selector B at signal S^C , for example, is as follows: from battery 27, through transmitting apparatus P, line wire 28, wires 30, 31 and 32 at signal S^C , retardation coil 33, resistance 34, operating winding 35 of selector B, retardation coil 36, wires 37 and 38, line wire 29, and transmitting apparatus P to battery 27. Selector H at signal S^C , and the two selectors B and H at each signal S^B and S^A , are also connected across the line wires 28 and 29, so that the same impulse combination is received by each selector, but we will assume that selector B at signal S^C is the only one which responds to the particular combination transmitted by key A in the despatcher's office. By the response of selector B we mean that contact 2 of this selector becomes closed. When contact 2 becomes closed, it remains closed until the operating winding 35 becomes energized by another impulse combination transmitted over the line 28, 29, or until a single impulse is transmitted over the line by suitable means such as a key R in the despatcher's office which when closed causes relay 24 to close. When contact 2 closes it causes a repeating relay C to be energized by virtue of a circuit which passes from battery 12, through wires 39, 40 and 41, contact 2 of selector B, right-hand winding 42 of this selector, wires 43 and 44, winding of relay C, and wires 45 and 46 to battery 12. It will be noted that the circuit for relay C includes a selector winding 42 which may be termed a holding winding. This winding is located on the magnet core of the selector and so it is in inductive relation to the operating winding 35. The function of winding 42 will be explained hereinafter. The operation of relay C closes at contact 3 a pick-up circuit for a stick relay D, which circuit passes from battery 11, through wires 47, 48 and 49, contact 3 of relay C, wires 50 and 51, winding of relay D, and wires 52, 53, and 54 to battery 11. As soon as relay D closes, a stick or holding circuit for this relay is closed, which circuit passes from battery 11, through wires 47, 48, 55, 56 and 57, contact 4 associated with signal S^C , wire 59, contact 5 of a thermal circuit controller Q, wire 60, contact 61 of relay D, wire 51, winding of relay D, and wires 52, 53 and 54 to battery 11. As will be explained in detail hereinafter, contact 4, which is associated with signal S^C , is normally closed but is opened momentarily just before the signal reaches the stop position. As for the thermal circuit controller Q, it will be sufficient for the present discussion to assume that contact 5 is always closed, but as will appear hereinafter, this contact is opened at certain times for protective purposes.

Assuming that signal S^C is in the proceed or the caution position, the closing of relay D closes a circuit to a bell E, which circuit is from battery 12, through wires 39, 40 and 41, contact 2 of selector B, winding 42, wires 43 and 62, contact 63 of relay D, wire 64, contact 65 operated by signal S^C , wire 66, bell E, and wires 67, 75 and 46 to battery 12. The current in this circuit will be intermittent due to the operation of the bell, and this intermittent current in winding 42 of selector B will induce impulses in selector winding 35. These impulses will consequently be impressed on line wires 28 and 29, and so will be heard in a despatcher's telephone N^P which is connected across the line wires in office Z. The winding 42 has relatively few turns, and the voltage of battery 12 is relatively low, so that the ampere turns produced by this winding are not sufficient to actuate the selector armature and so to release the contact 2. It will be observed that the circuit for bell E, giving information that the condition has properly been set up by the closing of contact 63 of relay D, includes contact 65, which is closed when signal S^C indicates proceed or caution and is open when this signal indicates stop. It follows, therefore, that if the despatcher receives the annunciation from bell E, he is informed that signal S^C indicates either proceed or caution, and that the condition to receive indication when the signal moves to stop has been properly set up.

The stick relay D will remain closed until contact 4 is opened, that is, until a train passes signal S^C , at which time signal S^C will of course move to the stop position, and as we have already stated, contact 4 opens for a moment just before this position of the signal is reached. The movement of signal S^C from proceed or caution position to stop position will also cause operation of a code wheel 6 as explained hereinafter which in turn will cause intermittent operation of a telegraph relay 7 by virtue of a circuit which passes from battery 12, through wires 39, 40 and 68, contact 169 operated by code wheel 6, resistance 69, wire 70, winding of relay 7, wire 71, contact 73 of relay D, and wires 74, 75 and 46 to battery 12. This operation of relay 7 causes an impulse combination to be sent out from a transmission device P^C . The upper terminal of this device is connected with line wire 29 by wires 37 and 38, whereas the lower terminal is connected with line wire 28 by means of wire 116, contact 117 of relay D, and wires 118 and 30. The impulse combination is consequently impressed on the line wires 28 and 29, and so is received by three selectors F^A , F^B and F^C , which are connected across the transmission line in the despatcher's office Z. Selector F^C responds to the impulse combination from the transmitting device P^C , and the conse-

quent closing of contact 8 of this selector closes a circuit for relay M^c , which circuit passes from battery 16, through wires 79, 81, 82, and 83, contact 8, right-hand winding 84 of selector F^c , wire 85, winding of relay M^c , wires 86, 87, and 88, manually operable key 17, and wire 89 to battery 16. The closing of relay M^c closes at contact 22 a circuit for a lamp L^c , which circuit passes from the secondary of a transformer U, through wire 90, lamp L^c , wire 91, contact 22, and wire 92 to the secondary of transformer U. The primary of transformer U is connected with an alternating current transmission line 93, which in practice will usually be an electric lighting line. The lighting of lamp L^c indicates to the despatcher that a train has passed signal S^c .

The momentary opening of contact 4 just before signal S^c reaches the stop position opens the holding circuit for relay D, so that this relay becomes de-energized. The parts of the apparatus are then restored to the conditions in which they are shown in the drawing.

We will now assume that signal S^c is in the proceed or caution position, and that the despatcher desires to place this signal at stop. To accomplish this the despatcher first operates his code key A, thereby causing relay D to close as before. He then operates his code key G, which key transmits the impulse combination to which selector H in signal S^c responds. While contact 9 of this selector is closed, a repeating relay J is energized by virtue of a circuit which passes from battery 12, through wires 39 and 94, contact 9, winding 95, wires 96 and 97, relay J, wires 98, 45 and 46, to battery 12. The closing of contact 10 of relay J closes a pick-up circuit for a stick relay K, which circuit passes from battery 11, through wires 47, 48, 55, 56 and 100, contact 10 of relay J, wire 101, contact 13 of relay D, wire 102, winding of relay K, and wires 103, 53 and 54 to battery 11. As soon as relay K closes, a stick circuit for this relay becomes closed, which circuit passes from battery 11, through wires 47, 48, 55, and 107, back contact 14 of relay C, wire 108, contact 109 of relay K, wire 110, winding of relay K, and wires 103, 53 and 54 to battery 11. The closing of relay K opens at back contact 15 the caution indication circuit for signal S^c , which circuit is from battery 11, through wires 47 and 111, back contact 15, wire 112, contact 113 of track relay T^c , wire 114, operating mechanism of signal S^c , and wires 115 and 54 to battery 11. Signal S^c then moves to the stop position. When a train reaches signal S^c , it will, of course, come to a stop and the train crew can then communicate with the despatcher by means of a telephone N^c which is located adjacent signal S^c and is connected across the line 28-29. Having placed signal S^c in the stop position the despatcher can restore it to caution or proceed position by operating code key A, thereby actuating selector B, which in turn energizes relay C. The opening of back contact 14 of relay C opens the stick circuit for relay K, so that the caution indication circuit for signal S^c is again closed at contact 15, whereupon the signal returns to the caution or proceed position, provided that traffic conditions in advance of this signal are such as to permit the signal to assume one of these positions or the other.

We will now assume that signal S^c is in stop position, and that the despatcher operates code keys A and G successively. Key A causes relay D to close as before, but bell E will not operate because its circuit is open at contact 65. Key G will cause relay K to close as before, whereupon the following circuit for the bell will be closed—from battery 12 through wires 39 and 94, contact 9 of selector H, winding 95 of this selector, wires 96 and 172, contact 173 of relay K, wire 174, contact 65, wire 66, bell E, and wires 67, 75 and 46 to battery 12. The intermittent current in this circuit due to bell E will cause impulses to be induced in line wires 28 and 29 by virtue of transformer action in selector H, and so the despatcher will know by the sound in his telephone N^c that the signal is at stop. By this means the despatcher is informed that the block controlled by signal S^c is occupied, and so he is enabled by trial to locate a train. The annunciation may be discontinued as before by operating key R.

One important feature of the apparatus is that, even though a signal is at stop owing to the presence of a train, the signal may be held in this position to stop a following train, this being accomplished by the necessary steps on the part of the despatcher to close relay K. The despatcher can subsequently place the signal in condition to clear when the block becomes unoccupied, this being done as before by causing relay K to open.

Although we have shown only two code keys A and G in the despatcher's office Z, it is understood that a similar pair of keys will be provided for each signal which is controlled from this office. That is to say, a similar pair of keys will be provided for the operation of selectors B and H at signal S^c , and a third pair of keys will be provided for the operation of selectors B and H at signal S^a .

We will now assume that the despatcher desires to trace the movement of a train from the time that it passes signal S^a to the time that it passes signal S^c . To do this he operates each of his indication code keys A, thereby closing contact 2 in the selector B at each signal S^a , S^b and S^c . This results

in energizing relay D at each signal. When a train passes signal S^A the consequent movement of this signal to the stop position transmits an impulse combination over the line wires 28 and 29 which actuates selector F^A in the despatcher's office. While contact 8 of this selector is closed, a pick-up circuit for relay M^A is closed, which circuit passes from battery 16, through wires 79, 81, 82, 119 and 120, contact 8 of selector F^A , winding 121 of this selector, wire 122, winding of relay M^A , wires 123 and 88, key 17, and wire 89 to battery 16. As soon as relay M^A closes, a stick circuit for this relay becomes closed, which circuit passes from battery 16, through wires 79, 124, and 125, back contact 18 of relay M^B , wire 126, contact 127 of relay M^A , wire 128, winding of relay M^A , wires 123 and 88, key 17, and wire 89 to battery 16. The closing of relay M^A closes a circuit for lamp L^A , which circuit passes from transformer U, through wire 90, lamp L^A , wire 129, contact 19 of relay M^A , and wires 130 and 92 to transformer U. When the train passes signal S^B it sends an impulse combination over the line wires 28 and 29 which causes operation of the selector F^B in the despatcher's office. While contact 8 of this selector is closed relay M^B is energized by a circuit which passes from battery 16, through wires 79, 81, 82 and 119, contact 8 of selector F^B , winding 131 of this selector, wire 132, winding of relay M^B , wires 87 and 88, key 17, and wire 89 to battery 16. As soon as relay M^B closes, a stick circuit for this relay is closed, which circuit passes from battery 16, through wires 79 and 81, back point of contact 20 of relay M^C , wire 133, contact 134 of relay M^B , wire 135, winding of relay M^B , then through 87, 88, 17 and 89 to battery 16. Contact 21 of relay M^B closes a circuit for lamp L^B , which circuit is from transformer U, through wire 90, lamp L^B , wire 136, contact 21 of relay M^B , and wires 137 and 92 to transformer U. When relay M^B closes, the stick circuit for relay M^A is opened at back contact 18, so that the latter relay becomes de-energized and lamp L^A becomes extinguished. When the train passes signal S^C relay M^C becomes energized, as explained hereinbefore, thereby causing lamp L^C to become lighted. Relay M^C remains closed until the despatcher closes his key R or another calling key has been operated. The closing of relay M^C also opens at the back point of contact 20 the stick circuit for relay M^B so that lamp L^B becomes extinguished.

Assuming that relay M^A has been energized by a train passing signal S^A , the despatcher can de-energize this relay at will by opening key 17, thereby opening the holding circuit for relay M^A . Relays M^B and M^C can be de-energized at will in the same manner.

The function of the thermal circuit controller Q, is as follows: As will be apparent from Fig. 1^A, each time that the telegraph relay 7 of the transmitting device P^C is closed, it causes a momentary connection 70 across the line wires 28 and 29 through battery 76 and contact 117 of relay D. If the code wheel contact 169 or the telegraph line relay 7 should stick in the closed position, this short circuit would tie up the apparatus 75 in so far as concerns the control of the signals from the despatcher's office and the indication of signal operation in the despatcher's office. To avoid this difficulty we have provided the thermal circuit controller Q. The 80 normally closed contact 5, as pointed out hereinbefore, is included in the holding circuit for the indication stick relay D. The circuit for the winding of the device Q is from a battery 138, through wire 139, contact 140 of relay D, wire 141, winding 142 of circuit controller Q, wire 143, contact 144 of telegraph relay 7, and wire 145 to battery 138. During the normal operation of the transmitting device P^C , contact 144 is closed 85 intermittently for short intervals, but these intervals are not sufficient to heat the device Q to such point that contact 5 will open. If, however, contact 169 or the telegraph relay 7 should stick in the closed position, contact 90 95 100 105 110 115 120 125 130 135 140 145 150 155 160 165 170 175 180 185 190 195 200 205 210 215 220 the caution position it of course has no effect on the arm 149 and shaft 147, but when the signal returns to the stop position these parts are restored to their normal position by 5 spring 148.

Attached to the inner end of shaft 147 is a ratchet 152 which co-operates with a pawl 153 on a gear wheel 154, which gear wheel is otherwise free to rotate with respect to the 10 shaft. The arrangement of the pawl and ratchet is such that when the shaft is swung in clockwise direction by the signal, the gear wheel does not revolve, but that this gear wheel is positively connected with the shaft 15 when the latter returns under the influence of spring 148. Meshing with gear wheel 154 is a small gear 155 fixed to a shaft 156 which carries the code wheel 6. The ratio of these 20 two gears is such that the code wheel makes one complete revolution while the shaft 147 is making its usual 90° movement from the vertical to the horizontal position of arm 149. The code wheel co-operates with the contact 169 in the usual and well known manner, so 25 that this contact is closed by each tooth on the wheel.

The speed of operation of the code wheel by spring 148 is limited by a centrifugal speed governor 159 which is operatively connected with code wheel shaft 156 through 30 the medium of gears 160.

In order to stop the code wheel 6 at the proper place, the shaft 147 carries a Z shaped pawl 161 which co-operates with a pin 162 fixed in the code wheel. When the 35 shaft is swung in clockwise direction by the signal, the pawl moves downwardly out of the path of the pin, so that the code wheel can revolve when the parts are released, but as the shaft approaches its normal or biased 40 position this pawl returns to its position in the path of the pin and so arrests the moving parts just as the operation of the code wheel is completed.

45 The auxiliary contact 4 is normally closed, but is momentarily opened by the pin 162 on code wheel 6 just before this wheel comes to rest, that is, when the signal has reached the stop position.

50 As shown in Fig. 5 the code wheel 6 makes only one revolution while the signal is moving from the caution to the stop position, but if desired the code wheel may be caused to make two or more revolutions during such 55 movement of the signal, so that the impulse combination transmitted by this wheel will be impressed on the line two or more times in succession, thereby increasing the probability of the successful response of the corresponding selector in the despatcher's office. This may be accomplished by adding a gear wheel 170 and pinion 171 between wheel 154 and pinion 155 as shown in Fig. 6.

60 Referring now to Figs. 7, 8 and 9, we have 65 here illustrated one form of thermal circuit

controller Q which may be used in the system shown in Fig. 1. This controller comprises a base 163 of insulating material on which is mounted an element 164 of heat responsive material provided with a winding 165. 70 The terminals of this winding are attached to binding posts 166 and 166a. Also mounted on the base 163 is a yoke 167 carrying an adjustable screw 168 which, with the element 164, constitutes the contact 5 of the circuit 75 controller. At normal temperature this contact is closed, but when the element 164 is heated due to prolonged supply of current to winding 165, this element bends downwardly out of engagement with the screw 80 168 so that contact 5 is then open.

85 Although we have herein shown and described only one system embodying our invention, and only a few forms of apparatus for use in such system, it is understood that various changes and modifications may be made therein within the scope of the appended claims without departing from the spirit and scope of our invention.

90 Having thus described our invention, what we claim is:

1. In combination, a series of railway traffic controlling devices, apparatus for each device including a code key set into operation upon movement of the device for transmitting a distinctive impulse combination, a series of selectors located at a central point and responding to said distinctive impulse combinations respectively, and means controlled by said selectors for indicating 95 operation of said devices.

100 2. In combination, a railway signal; a selector comprising an operating winding, an auxiliary winding and a normally open contact which is closed when the operating winding receives the impulse combination to which the selector responds; a circuit including said contact and said auxiliary winding and a repeater relay, a stick relay, a pick-up circuit for said stick relay controlled by said repeater relay, a holding circuit for said stick relay controlled by a contact operated by said signal, an indicating device, and a circuit for said device controlled by said signal and by said stick relay and by said selector contact.

110 3. In combination, a railway signal, two 105 selectors associated therewith and selectively responsive to two different impulse combinations, means controlled by said selectors for placing said signal at stop or proceed, and means including two code keys under the control of a despatcher at a distant point for transmitting said two impulse combinations to said selectors.

120 4. In combination, a railway signal, a stick relay, means controlled by said relay when energized for causing a change in the 125 indication given by said signal, means including a selector at the signal and a code

key at a distant point for closing said relay, and means for subsequently keeping said relay closed until the change of indication of said signal has been accomplished, when said relay is closed to give a positive indication if said signal is at proceed.

5. In combination, a railway signal, a stick relay, means controlled by said relay when energized for causing a change in the indication given by said signal, means including a selector at the signal and a code key at a distant point for closing said relay, means for subsequently keeping said relay closed until the change of indication of said signal has been accomplished, and means controlled by said relay when closed for giving positive information at said distant point of the indication given by said signal.

6. In combination, a railway signal, a code key associated therewith, means responsive to a change in the indication given by said signal for causing operation of said code key, a selector located at a distant point and responsive to the impulse combination transmitted by said code key, and indicating means controlled by said selector.

7. In combination, a railway signal, a stick relay associated therewith, means including a selector at the signal and a code key at a distant point for closing said relay, means for subsequently keeping said relay closed until said signal changes to the stop indication, and means controlled by said relay when closed for giving a positive indication at said distant point if said signal is giving a proceed indication.

8. In combination, a railway signal, a stick relay associated therewith, means including a selector at the signal and a code key at a distant point for closing said relay, means for subsequently keeping said relay closed until said signal changes to the stop indication, and means controlled jointly by said relay and by said selector and effective while the relay is closed and the selector has responded to operation of said code key, to give a positive indication at said distant point if said signal is in a proceed condition.

9. In combination, a railway signal, a stick relay associated therewith, means including a selector at the signal and a code key at a distant point for closing said relay, means for subsequently keeping said relay closed until said signal changes to the stop indication, and means effective if said relay is closed to give an indication at said distant point when said signal changes to the stop condition.

10. In combination, a railway signal, a stick relay associated therewith, means including a selector at the signal and a code key at a distant point for closing said relay, means for subsequently keeping said relay closed until said signal changes to the stop indication, and means including a vibrating device at said signal and a telephone receiver at said distant point and operating

7. In combination, a stick relay associated therewith, means including a selector at the signal and a code key at a distant point for closing said relay, means for subsequently keeping said relay closed until said signal changes to the stop indication, a vibrating device adjacent said signal, means for operating said device when said relay is closed and the signal is at proceed, and means including a telephone receiver at said distant point for detecting operation of said device.

12. In combination, a railway signal, a stick relay associated therewith, means including a selector at the signal and a code key at a distant point for closing said relay, means for subsequently keeping said relay closed until said signal changes to the stop indication, a vibrating device adjacent said signal, means for operating said device after said relay closes and said selector has responded to its code key provided said signal is at proceed, and means for detecting operation of said vibrating device at said distant point.

13. In combination, a railway signal, a stick relay associated therewith, means including a selector at the signal and a code key at a distant point for closing said relay, means for subsequently keeping said relay closed until said signal changes to the stop indication, and means including a code key operated by said signal and a selector at said distant point for indicating when said signal changes to the stop condition if said relay is closed at such time.

14. In combination, a railway signal, a stick relay associated therewith, means including a selector at the signal and a code key at a distant point for closing said relay, means for subsequently keeping said relay closed until said signal changes to the stop indication, a selector at said distant point, means including a code key actuated by said signal and operating when the signal moves to the stop position if said relay is closed to transmit to said second selector the impulse combination to which it responds, and indicating means controlled by said second selector.

15. In combination, a railway signal, a stick relay associated therewith, means including a selector at the signal and a code key at a distant point for closing said relay, means for subsequently keeping said relay closed until said signal changes to the stop indication, a selector at said distant point, means including a code key actuated by said signal and operating when the signal moves to the stop position if said relay is closed to transmit to said second selector the impulse combination to which it responds, a lamp at said distant point, and means for

lighting said lamp when the selector at said point receives the impulse combination to which it responds.

16. In combination, a railway signal, a selector associated therewith, and including a contact which becomes closed when the selector receives the impulse combination to which it responds, means including a code key at a distant point for transmitting said impulse combination to said selector, and means controlled jointly by said selector and said signal and operating if the signal is at proceed while the selector contact is closed to give a positive indication at said distant point.

17. In combination, a railway signal, a selector associated therewith, and including a contact which becomes closed when the selector receives the impulse combination to which it responds, means including a code key at a distant point for transmitting said impulse combination to said selector, a vibrating device associated with said signal, means for operating said device while said selector contact is closed if said signal then indicates proceed, and means including a telephone receiver at said distant point for detecting operation of said vibrating device.

18. In combination, a railway signal, a code key actuated by said signal for transmitting an impulse combination, and indicating means for said signal including a selector at a distant point responsive to the impulse combination transmitted by said code key.

19. In combination, a railway signal, a code key actuated by said signal for transmitting an impulse combination, a selector located at a distant point and responsive to the impulse combination transmitted by said code key, a lamp at said distant point, and means for lighting said lamp when said selector receives the impulse combination to which it responds.

20. In combination, a railway signal, a code key actuated by said signal for transmitting an impulse combination, a selector located at a distant point and responsive to the impulse combination transmitted by said code key, a lamp at said distant point, means for lighting said lamp when said selector receives the impulse combination to which it responds, means for subsequently keeping said lamp lighted, and manually operable means for extinguishing said lamp.

21. In combination, a railway signal, a transmission line extending from said signal to a distant point, a code key actuated by said signal for impressing an impulse combination on said line, and indicating means at said distant point including a selector connected with said transmission line and responsive to the impulse combination delivered by said code key.

22. In combination, a railway signal, a code key associated therewith, means re-

sponsive to a change in the indication given by said signal for causing operation of said code key, a selector located at a distant point and responsive to the impulse combination transmitted by said code key, a lamp, and means for lighting said lamp when said selector receives the impulse combination to which it responds.

23. In combination, a railway signal, two selectors associated therewith, and responsive to two different impulse combinations, means including two code keys located at a distant point for transmitting said impulse combinations to said selectors, a relay, means for closing said relay when one selector responds to its impulse combination, means for subsequently keeping said relay closed, means for placing said signal at stop when said relay is closed, and means for opening said relay when the other selector responds to its impulse combination.

24. In combination, a railway signal, two selectors associated therewith and responsive to two different impulse combinations, means including two code keys located at a distant point for transmitting said impulse combinations to said selectors, and means operating to place said signal at stop when said two selectors respond successively to their respective impulse combinations.

25. In combination, a railway signal, two selectors associated therewith and responsive to two different impulse combinations, means including two code keys located at a distant point for transmitting said impulse combinations to said selectors, a repeating relay for each selector, means for closing each repeating relay when the corresponding selector responds to its impulse combination, a stick relay for each repeating relay, a pick-up circuit for the first stick relay controlled by a front contact of the associated repeating relay, a holding circuit for said first stick relay, a pick-up circuit for the second stick relay controlled by a front contact of the associated repeating relay and a front contact of the first stick relay, a holding circuit for the second stick relay controlled by a back contact of the first repeating relay, and an operating circuit for said signal controlled by second stick relay.

26. In combination, a railway signal, two selectors associated therewith and responsive to two different impulse combinations, means including two code keys located at a distant point for transmitting said impulse combinations to said selectors, means operated by the successive response of said two selectors for placing said signal at stop, and means operated by the subsequent response of one of said selectors for restoring said signal to proceed.

27. In combination, a railway signal, a code key associated therewith, means responsive to a change in the indication given by

said signal for causing operation of said code key, a selector located at a distant point and responsive to the impulse combination transmitted by said code key, a lamp, means for lighting said lamp when said selector receives the impulse combination to which it responds, and means for subsequently keeping said lamp lighted.

28. In combination, a series of railway signals, a transmission line extending from said signals to a distant point, a code key associated with each signal, for impressing a distinctive impulse combination on said transmission line, a series of selectors located at said distant point and receiving impulses from said transmission line and each selectively responsive to the impulse combination of one of said code keys, and indication means controlled by said selectors.

29. In combination, a series of railway signals, apparatus for each signal including a code key operated by the signal for transmitting a distinctive impulse combination, a series of selectors, located at a central point and responding to said distinctive impulse combinations respectively, and means controlled by said selectors for indicating operation of said signals.

30. In combination, a series of railway signals, apparatus for each signal including a code key operated by the signal for transmitting a distinctive impulse combination, a series of selectors located at a central point and responding to said distinctive impulse combinations respectively, a relay associated with each selector, means controlled by each selector when operated by its distinctive impulse combination for closing the associated relay, and an indication device controlled by each relay.

31. In combination, a series of railway signals, apparatus for each signal including a code key operated by the signal for transmitting a distinctive impulse combination, a series of selectors located at a central point and responding to said distinctive impulse combinations respectively, a relay associated with each selector, a pick-up circuit for each relay closed when the associated selector responds to its distinctive impulse combination, a holding circuit for each relay except the last in the series controlled by a back contact of the next relay in the series, and indication devices controlled by said relays.

32. In combination, a series of railway signals, apparatus for each signal including a code key operated by the signal for transmitting a distinctive impulse combination, a series of selectors located at a central point and responding to said distinctive impulse combinations respectively, a relay associated with each selector, a pick-up circuit for each relay closed when the associated selector responds to its distinctive impulse combination, a holding circuit for each relay

except the last in the series controlled by a back contact of the next relay in the series, manually operable means for opening each holding circuit, and indication devices controlled by said relays.

33. In combination, a series of railway signals, apparatus for each signal including a code key operated by the signal for transmitting a distinctive impulse combination, a series of selectors located at a central point and responding to said distinctive impulse combinations respectively, a relay associated with each selector, means for closing each relay when the associated selector responds and for keeping it closed until the next relay closes, and indication devices controlled by said relays.

34. In combination, a series of railway signals, apparatus for each signal including a code key operated by the signal for transmitting a distinctive impulse combination, a series of selectors located at a central point and responding to said distinctive impulse combinations respectively, indication lamps associated with said selectors, and means for lighting each lamp upon the response of the associated selector and for keeping it lighted until the next selector in the series responds.

35. In combination, a series of railway signals, apparatus for each signal including a code key operated by the signal for transmitting a distinctive impulse combination, a series of selectors located at a central point and responding to said distinctive impulse combinations respectively, indication devices associated with said selectors, and means for operating each device upon the response of the associated selector and for continuing the operation of such device until the response of the next selector in the series.

36. In combination, a series of railway signals, apparatus for each signal including a code key operated by the signal for transmitting a distinctive impulse combination, a series of selectors located at a central point and responding to said distinctive impulse combinations respectively, and means under the control of an operator at said central point for connecting the transmitting apparatus of any one or more of said signals with said selectors.

37. In combination, a series of railway signals, apparatus for each signal including a code key operated by the signal for transmitting a distinctive impulse combination, a series of selectors located at a central point and responding to said distinctive impulse combinations respectively, and means comprising code keys at said central point and selectors at said signals for connecting the transmitting apparatus of any one or more of the signals with said first-mentioned selectors.

38. In combination, a series of railway signals, a despatcher's office, a transmission line extending from said office to said signals, a selector at each signal connected with said transmission line, means in said office for impressing impulse combinations on said line and including a code key corresponding to each signal selector, a relay at each signal, means for closing each relay when the corresponding selector responds to its impulse combination and for subsequently keeping the relay closed until the associated signal moves to the stop position, means for each signal including a code key operated by the signal for impressing a distinctive impulse combination on said line when the associated relay is closed, selectors in said office connected with said line and individually responsive to the impulse combinations transmitted from said signals, and indicating means in said office controlled by said office selectors. 70
39. In combination, a series of railway signals, a despatcher's office, a transmission line extending from said office to said signals, a selector at each signal connected with said transmission line, means in said office for impressing impulse combinations on said line and including a code key corresponding to each signal selector, a relay at each signal, means for closing each relay when the corresponding selector responds to its impulse combination and for subsequently keeping the relay closed until the associated signal moves to the stop position, a second selector at each signal and also connected with said line, additional code keys in said office corresponding to said second signal selector, and means associated with each signal for placing the signal at stop when the first and second associated selectors are operated in sequence by their respective combinations. 80
40. In combination, a railway traffic controlling device, a transmission line, apparatus associated with said device for impressing an impulse combination on said line, and means for disconnecting said apparatus from said line if the apparatus should stick in such conditions as to form an electrical connection across the line. 85
41. In combination, a railway traffic controlling device, a transmission line, apparatus associated with said device for impressing an impulse combination on said line, and means including a thermal circuit controller for disconnecting said apparatus from said line if the apparatus should stick in such condition as to form an electrical connection across the line. 90
42. In combination, a railway traffic controlling device, a transmission line, apparatus associated with said device for impressing an impulse combination on said line, a relay for connecting said apparatus with said line when the relay is energized, and means for de-energizing said relay if the apparatus should stick in such condition as to form an electrical connection across the line. 95
43. In combination, a railway traffic controlling device, a transmission line, apparatus associated with said device for impressing an impulse combination on said line, said apparatus including a source of current and an intermittently closing contact, a relay arranged when energized to connect said apparatus with said line, a circuit for said relay including a normally closed contact of a thermal circuit controller, and a circuit for the winding of said circuit controller including a second intermittently closing contact operated in unison with the first contact. 100
44. In combination, a railway traffic controlling device, a transmission line, apparatus associated with said device for impressing an impulse combination on said line, said apparatus including a source of current and an intermittently closing contact, a relay arranged when energized to connect said apparatus with said line, and means including a second intermittently closing contact operating in unison with the first said contact for de-energizing said relay if said contacts remain closed for more than a given length of time. 105
45. In combination, a railway traffic controlling device, a transmission line, apparatus associated with said device for impressing an impulse combination on said line, said apparatus including a source of current and an intermittently closing contact, and means associated with said apparatus for disconnecting the apparatus from said line if said contact remains closed for more than a given length of time. 110
46. In combination, a railway signal, a selector having a normally open contact which becomes closed when the selector receives the impulse combination to which it responds, and remains closed until the selector subsequently receives an impulse, a stick relay, means including said selector contact for closing said stick relay, means for subsequently keeping said relay closed until said signal changes to the stop indication, and means controlled by said relay and by said selector contact for giving an indication at a distant point if said signal indicates proceed. 115
47. In combination, a railway signal, a selector having a normally open contact which becomes closed when the selector receives the impulse combination to which it responds, and remains closed until the selector subsequently receives an impulse, a stick relay, means including said selector contact for closing said stick relay, means controlled by said signal for subsequently keeping said relay closed, and means controlled by said relay and by said selector 120
- 125
- 130

- contact for giving an indication at a distant point of the condition of said signal.
48. In combination, a railway signal, a selector having a normally open contact which becomes closed when the selector receives the impulse combination to which it responds, and remains closed until the selector subsequently receives an impulse, a stick relay, means including said selector contact for closing said stick relay, means controlled by said signal for subsequently keeping said relay closed, indication apparatus for said signal controlled jointly by said relay and said selector contact, and other indication apparatus for said signal controlled by said relay but not by said selector contact. 70
49. In combination, a railway signal, a selector having a normally open contact which becomes closed when the selector receives the impulse combination to which it responds, and remains closed until the selector subsequently receives an impulse, a stick relay, means including said selector contact for closing said stick relay, means for subsequently keeping said relay closed until said signal changes to the stop indication, means operating when said relay and said selector contact are closed to give an indication at a distant point while said signal is giving a proceed indication, and means controlled by said relay for giving an indication at said distant point when said signal changes to stop. 80
50. In combination, a transmission line, a plurality of selectors connected with said line and responsive to different impulse combinations, each selector including a normally open contact which is closed when the selector receives the impulse combination to which it responds, and remains closed until another impulse is impressed on said line, railway signals, and indication means for said signals controlled by said selector contacts. 85
51. In combination, a transmission line, a plurality of selectors connected with said line and responsive to different impulse combinations, each selector including a normally open contact which is closed when the selector receives the impulse combination to which it responds, and remains closed until another impulse is impressed on said line, railway signals, a stick relay for each selector, means for each stick relay including the contact of the associated selector for closing the relay, holding circuits for said relays controlled by said signals, indication means for said signals controlled jointly by said relays and said selector contacts, and other indication means for said signals controlled by said relays but not by said selector contacts. 100
52. In combination, a railway signal, a selector having a normally open contact which becomes closed when the selector receives the impulse combination to which it responds, and remains closed until the selector subsequently receives an impulse, a stick relay, means including said selector contact for closing said stick relay, means controlled by said signal for subsequently keeping said relay closed, indication apparatus for said signal controlled jointly by said relay and said selector contact, and other indication apparatus for said signal controlled by said relay but not by said selector contact. 105
53. In combination, a railway signal, a despatcher's station, a transmission line extending from said signal to said station, a selector at the signal having its operating winding connected with said line, said selector having an auxiliary winding in inductive relation to said operating winding, means at said station for impressing on said line the impulse combination to which said selector responds; a circuit including said auxiliary winding, the selector contact, means for supplying periodic current, and a contact controlled by said signal; and a telephone receiver connected with said line at the despatcher's station. 90
54. In combination, a transmission line, a selector having its operating winding connected with said line and having an auxiliary winding in inductive relation to said operating winding, means for impressing on said line the impulse combination to which said selector responds, a circuit including said auxiliary winding and controlled by the selector contact, means for supplying a periodic current to said circuit, a railway traffic controlling device for controlling said circuit, and a receiving device connected with said line for detecting the alternating current impressed on the line by said operating winding due to periodic current in said auxiliary winding. 105
55. In combination, a transmission line, a selector having its operating winding connected with said line and having an auxiliary winding in inductive relation to said operating winding, means for impressing on said line the impulse combination to which said selector responds, a circuit controlled by the contact of said selector and including said auxiliary winding means for supplying periodic current to said circuit, a railway signal, a contact operated by said signal for controlling said circuit, and a receiving device connected with said line for detecting the alternating current impressed on the line by said operating winding due to periodic current in said auxiliary winding. 110
56. In combination, a transmission line, a selector having its operating winding connected with said line and having an auxiliary winding in inductive relation to said operating winding, means for impressing on said line the impulse combination to which said selector responds, a railway sig- 125
- 130

nal, and means controlled by the contact of said selector and including the two windings thereon for giving an indication at a distant point through said transmission line 5 of the condition of said signal.

57. In combination, a railway signal, a selector having a normally open contact which becomes closed when the selector receives the impulse combination to which it 10 responds, said selector also having an auxiliary winding in inductive relation to its operating winding, and indication apparatus associated with said signal and including said auxiliary winding.

58. In combination, a transmission line, two selectors having their operating windings connected with said line and responsive to different impulse combinations and each having an auxiliary winding in inductive 15 relation to its operating winding, means for impressing on said line the impulse combinations to which said selectors respond, a circuit for the auxiliary winding of each selector and controlled by the contact of the same selector, means for supplying periodic current to each of said circuits, a railway signal, means controlled by said signal for closing one of said circuits or the other according as said signal gives one indication or another, and a receiving device connected 20 with said line for detecting the alternating current impressed on the line by the operating windings of said selectors due to the periodic current in said auxiliary windings.

In testimony whereof we affix our signatures.

DANIEL W. RICHARDS.
HARRY P. HANCOCK.
